UNITED STATES PATENT OFFICE.

WILLIAM E. FICKLEN, OF NORFOLK, VIRGINIA.

METAL-REINFORCING FRAME FOR CONCRETE STRUCTURES.

1,392,315.

Specification of Letters Patent.

Patented Oct. 4, 1921.

Application filed January 24, 1914, Serial No. 814,051. Renewed January 8, 1920. Serial No. 350,244.

To all whom it may concern:

Be it known that I, WILLIAM E. FICKLEN, a citizen of the United States, and a resident of Norfolk, county of Norfolk, State of Virginia, have invented certain new and useful Improvements in Metal-Reinforcing Frames for Concrete Structures; and I do hereby declare the following to be a full, clear, and exact description of the invention, such as to enable any one skilled in the art to make and use the same, reference being had to the accompanying drawings, which form a part of the specification.

My invention relates to metal reinforcements for concrete structures, of that general type embodying side bars or members and transverse members and integral with and connecting the same, but differs from the heretofore known form wherein the structure is of the single-piece expanded metal type, in that my reinforce is composed of two separate bars, and the two bars arranged facing each other, the said bars being connected together by means of braces sheared from the outer edge of each bar in the plane of the bar, with the free end of each brace extended toward opposed bars, said braces being fastened at their free ends to unite said bars rigidly together.

In order that my invention may be more easily understood, the same is illustrated with reference to the accompanying drawings of which:

Figure 1 is a perspective view of one form of my invention.

Fig. 2 is a modification of the form shown in Fig. 1.

A represents a T bar having a wing or web 10, extending therefrom. B represents a similar bar also having a wing or web 11 extending therefrom.

Cut from the web 10 of the bar A longitudinally thereof is a portion 12, which is extended out from the bar, in a direction substantially perpendicular thereto. As many of these portions may be cut from the bar A as seem desirable, the points of integral connection of the extended portions 12 with the web 10 of the bar A being at predetermined intervals. It is to be understood that the length of the extended portions 12 which also is substantially the distance between the bars A and B in the completed structure may be changed to suit variable

conditions. Similarly shaped rods or bars 13 are also cut from the web 11 of the bar B. Holes 14 and 15 are cut respectively in the webs 10 and 11 of the bar A and B at points about half way between the integral connection of the perpendicular part or portion 12 in the bar A and at similar positions in the web 13 of the bar B. The holes are made in the two webs of such size as to permit the insertion therein of the ends of the rods 12 and 13, which ends are split as illustrated at 16 and hammered down and jammed so as to make a tight joint at the connection, or the ends may be welded to the web.

In the modification shown in Fig. 2 the cut out portion of the web 12^a and 13^a in each of the bars A and B is about one half the length of the cut out portion 12 and 13 of the bars in Fig. 1. These short bars 12^a and 13^a are extended out of the web and their ends are so constructed that they are made to overlap. They are secured together by rivets or bolts, or may be so constructed, with ribs or teats as to form small raised portions thereon which will meet for the purpose of electrically welding the ends together.

My invention, constructed as above described, furnishes all the elements required to reinforce a concrete beam. The bars A and B supply the necessary metal to resist the stresses at the top and bottom of the beam; and the transversely extending members 12, 13, 12^a, 13^a, 21 and 31 strengthen the web or portion between the top and bottom thereof. When the bars A and B are joined together, a complete frame or unit of great strength and rigidity, but made up of a relatively small amount of material, is the final result. My improved frame is also capable of use in other concrete constructions, such as partitions, walls, columns, and the like, as will be apparent to those skilled in the art.

The various parts, which assembled, form the entire structure, may be packed separately at the place of manufacture, shipped and assembled at the place of use in the way hereinbefore described. Great advantage due to convenience and saving of expense in shipping, results from this capability of the invention to be made in separate parts, at the place of manufacture and

to be assembled into a complete structure just before using.

Having thus described my invention, what I claim as new and desire to secure by Letters Patent is:

1. A reinforcement for concrete structures, comprising a pair of T-bars arranged with their webs toward each other, but spaced apart, stiffening members, cut from the edge of each of said webs and extending straight across to the web of the other, there being holes in each of said webs, and the ends of said stiffening members being split, passed into said holes, and secured in place.
- 15 2. A metal reinforcement for concrete structures composed of separately formed bars, each bar having portions sheared from the outer edge of and extended in the plane of the web of the bar and the bars arranged 20 face to face and spaced apart, with the sheared portions of each bar extended toward the op-

posed bar and secured to hold the bars in their spaced relation.

3. A metal reinforcement for concrete structures, composed of separately formed bars having webs, said bars being arranged with their webs facing each other, said webs having spacing members cut from the same, an end of each spacing member of one bar being integral with the web and the other end extended toward the other bar and fastened to the web thereof at points between the integral connections, said integral connections being thus alternately disposed.

In witness whereof I have hereunto set my hand at the city, county and State of New York, this 5th day of December, 1913.

WILLIAM E. FICKLEN.

In presence of—

JOHN J. RANAGAN,
AGNES C. O'CONNELL.
